RETRACTING TYPE THEATER CHAIR

John J. Roman and Merritt K. Orton, Grand Rapids, Mich., assignors to American Seating Company, Grand Rapids, Mich., a corporation of New Jersey

Application July 11, 1945, Serial No. 604,430

5 Claims. (Cl. 155—116)

1

The present invention relates to chairs, and more particularly to opera chairs of the retracting type for use in theaters, auditoriums, and the like.

The primary objects of the invention are to provide an improved opera chair of the retracting type which the occupant thereof may move rearwardly in order to permit unobstructed passage of persons in front of him without his having to rise from the seat; to provide such a chair having link-type seat mountings of simple and sturdy construction; to provide such a chair in which the use of rollers, with their attendant noise and necessity of lubrication, is eliminated; to provide such a chair which may be mounted as a unit on pre-installed standards in either straight or curved rows, and dismounted as a unit therefrom; and generally to provide a retracting chair which is effective in use, attractive in appearance, and reasonably economical in manufacture.

These objects are attained by the illustrative embodiments of the invention shown in the accompanying drawings, wherein:

Figure 1 is a front elevational view of an opera chair of the retracting type;

Figure 2 is a side elevational view of the same showing the seat and back in their forwardly moved positions, and showing the seat in upwardly folded position in broken lines;

Figure 3 is a side elevational view of the same showing the seat and back in rearwardly retracted position;

Figure 4 is an enlarged fragmentary side elevational view of parts thereof, as viewed from the line 4—4 of Figure 1;

Figure 5 is a sectional view of the same taken on line 5—5 of Figure 4;

Figure 6 is a sectional view of the same taken on line 6—6 of Figure 5;

Figure 7 is a sectional view of parts thereof taken on line 7—7 of Figure 4 showing the mounting members of the chair in different adjusted positions;

Figure 8 is an inside elevational view of a modified form of mounting member for the chair, and parts adjacent thereto; and

Figure 9 is a sectional view thereof taken on line 9—9 of Figure 8.

Referring now in detail to these drawings, the chair there shown is mounted between spaced upright standards 1 having arm rests 2 and upwardly and rearwardly extending horns 3 on the upper ends of which are mounted brackets 4 as by means of machine screws 5 which may be

2

threaded into the standards. A chair back 6 is mounted between the standards swingably about a horizontal axis, being pivotally connected at opposite sides thereof to brackets 4 on the standards 1.

Plates 7 of generally triangular form are pivotally connected at their rearward ends 8 to the back 6 below the mountings of the back on the standards. The upper forward ends of the plates 10 are pivotally connected at 9 to the upper ends of struts 10 the lower ends of which are pivotally connected at 11 to mounting members 12 on the lower portions of the standards.

The mounting members 12 are adjustable on 15 the standards both laterally and swingably about vertical axes, being provided with depending threaded shanks 13 which are thus adjustable between spaced lugs 14 on the standards 1. In this manner slight differences in distances between 20 standards may be compensated for, and also the angular disposition of standards in curved rows. (See Figure 7.) Nuts 15 threaded on the lower ends of the shanks 13 are tightened after the chair is installed to secure these parts in assembly.

In Figures 8 and 9 a modified form of mounting member is shown, which comprises a U-shaped strap 12¹ into the bight portion 12² of which is welded a depending pin 13¹ adjustable laterally and swingably about a vertical axis between spaced lugs 14¹ on the standard 1¹, and provided with nuts 15¹ on the lower ends thereof for securing these parts in assembly.

Referring now particularly to Figures 2—6 inclusive, a seat 16 is provided with supporting arms 17 on opposite sides thereof, which are pivotally connected at 18 to the plates 7, and the seat is thus mounted between the plates turnably to a lowered position for occupancy as indicated 30 in full lines in Figure 6 and to a raised position indicated in broken lines in the same view. The seat is supported in its lowered position by inwardly and upwardly extending lugs 19 on the plates 7 which engage in outwardly struck sockets 20 on the seat supporting arms 17.

The plates 7 are provided with laterally, outwardly extending cylindrical stops 21 having annular rubber cushioning members 22 thereon. The stops 21 extend into arcuate ways 23 pierced in the struts 10 and engage outwardly extending flanges 24, 25 at the ends of the ways 23 in the forward and rearward moved positions respectively of the seat 16, thus bringing the seat to a cushioned stop when moved to its forward position or retracted therefrom.

An equalizing bar 26 here shown as tubular in form has its opposite ends welded to the struts 10 thus insuring movement of the struts in unison so that no binding occurs between the various parts of the chair. Tension springs 27 have their forward ends secured to metal straps 28 welded on the equalizing bar 26 and their rearward ends secured to bosses 29 cast in the standards 1, and these springs normally maintain the seat in a retracted position when unoccupied.

The upper forward portions 30 of the plates 7 are preferably bent outwardly and downwardly to form protective shields to prevent the clothing of a chair occupant from becoming caught between the plates 7 and struts 10. Means are provided for cushioning the interrelative movement of the plates 7 and struts 10, comprising a pair of circular pads 31 of felt or the like secured as by rivets 32 to the opposite sides of each strut 10. A machine screw 33 extends through an opening 34 in the outer portion 30 of each plate 7, through an arcuate slot 35 in the adjacent strut 10, and is threaded in said plate 7. This screw 33 may be turned so as to adjust the space between the plate 7 and shield 30, to thus adjust the amount of friction exerted by the felt pads 31 on parts 7, 10 and 30.

It will thus be seen that the retracting chair shown and described is simply and sturdily constructed, and is designed for smooth and effective operation. It is to be understood that numerous details of the particular embodiments of the invention herein disclosed may be altered or omitted without departing from the spirit of the invention as the same is defined by the following claims.

We claim:

1. A chair comprising spaced upright standards; a back mounted on the standards swingably about a horizontal axis; plates pivotally connected at their rear ends to the opposite sides of the back below the mounting thereof and having depending portions provided with laterally projecting stops thereon; a seat mounted between the plates; and struts pivotally mounted at their lower ends on the standards and pivotally connected at their upper ends to said plates respectively, said struts having forwardly-rearwardly elongated portions approximately midway between their upper and lower pivotal connections and said portions being provided with forwardly-rearwardly extending ways into which the stops on the plates extend, said stops being adapted to engage the forward and rearward ends of said ways in the forwardly and rearwardly moved positions respectively of the seat.

2. A chair comprising spaced upright standards; a back mounted on the standards swingably about a horizontal axis; plates pivotally connected at their rear ends to the opposite sides of the back below the mounting thereof and having depending portions provided with laterally projecting stops thereon; a seat mounted between the plates; struts pivotally mounted at their lower ends on the standards and pivotally connected at their upper ends to said plates respectively, said struts having forwardly-rearwardly elongated portions approximately midway between their upper and lower pivotal connections and said portions being provided with forwardly-rearwardly extending ways into which the stops on the plates extend, said stops being adapted to engage the forward and rearward ends of said ways in the forwardly and rear-

wardly moved positions respectively of the seat; and cushioning members on said stops.

3. A chair comprising spaced upright standards; a back mounted on the standards swingably about a horizontal axis; plates pivotally connected at their rear ends to the opposite sides of the back below the mounting thereof and having stops thereon; a seat having supporting arms connected to said plates swingably about a horizontal axis; lugs on said plates and cooperating sockets on the seat adapted to engage said lugs to support the seat in its lowered position of use; and struts pivotally mounted at their lower ends on the standards and pivotally connected at their upper ends to said plates respectively, said struts having means thereon for engagement by said stops in forwardly and rearwardly moved positions respectively of the seat.

4. A chair comprising spaced upright standards; a back mounted on the standards swingably about a horizontal axis; plates pivotally connected at their rear ends to the opposite sides of the back below the mounting thereof and having stops thereon; a seat mounted between the plates; struts pivotally mounted at their lower ends on the standards and pivotally connected at their upper ends to said plates respectively, said struts having means thereon for engagement by said stops in forwardly and rearwardly moved positions respectively of the seat; a friction pad interposed between each plate and the adjacent strut for cushioning their interrelative movement; and an adjustment screw associated with each plate and with the adjacent strut for laterally adjusting each plate relatively to its adjacent strut in order to increase or decrease the friction between these members and the friction member interposed therebetween.

5. A chair comprising spaced upright standards each having horizontally spaced inwardly extending lugs on the lower portions thereof; a back mounted on the standards swingably about a horizontal axis; plates pivotally connected at their rear ends to the opposite sides of the back below the mounting thereof; a seat mounted between the plates; mounting members having depending shanks disposed between the lugs on the lower portions of said standards, said mounting members being adjustable laterally and swingably about vertical axes; means for securing the mounting members in adjusted positions; struts pivotally connected at their lower ends to the mounting members and pivotally connected at their upper ends to said plates respectively; and stop means for limiting the forward and rearward movements of the seat.

JOHN J. ROMAN,

MERRITT K. ORTON.
